UNITED STATES PATENT OFFICE.

MILTON H. HART, OF BROOKLYN, NEW YORK.

CELLAR-PIPE FOR EXTINGUISHING FIRES.

SPECIFICATION forming part of Letters Patent No. 691,858, dated January 28, 1902.

Application filed December 15, 1900. Serial No. 40,025. (No model.)

To all whom it may concern:

Be it known that I, MILTON H. HART, a citizen of the United States of America, residing in the borough of Brooklyn, city and State of New York, have invented certain new and useful Improvements in Cellar-Pipes for Extinguishing Fires, of which the following is a specification.

My improvement relates to pipes which are let down into cellars from a floor above to supply a current of water under control from the said floor for extinguishing a fire.

I will describe a cellar-pipe embodying my improvement and then point out the novel features in the claims.

Figure 1 is an elevation of a cellar-pipe embodying my improvement, and a sectional view of a floor above the cellar is also included in this figure. Fig. 2 shows the cellar-pipe, on a smaller scale, folded for transportation. Fig. 3 is a vertical section of a portion of the cellar-pipe on a larger scale than the other figures. Fig. 4 is a vertical section on the same scale as Fig. 3 and of the lower portion of the cellar-pipe.

Similar letters of reference designate corresponding parts in all the figures.

The cellar-pipe comprises two sections A' A², which are connected, by means of a hinge a', so that they may be folded close together, as illustrated in Fig. 2, and secured in that relation by means of a strap a². The hinge a' is connected with an elbow A³ and with a collar a³, surrounding the adjacent end of the section A'. A catch a', connected by a hinge a⁵ to the elbow A³, engages with a flange with which the collar a³ is provided at a point opposite the hinge a' to secure the section A' of the pipe in proper relation with the elbow A³ to conduct the water thereto.

The section A' is provided with feet or rests a⁶, which may be of any suitable form to rest upon the floor B above the cellar. It has also affixed to its underside a ring a⁷ for receiving a rod C, upon which a fireman may stand so as to hold the section A' of the pipe in position upon the floor B. This rod C may be withdrawn from the ring a⁷ and inserted at one end into a recess formed in that one of the feet a⁶ which is near the outlet end of the section A' of the pipe and inserted at the other end in that one of the feet a⁶ which is

near the inlet end of said section A'. To permit of this, the first-mentioned foot a⁶ is provided internally with a helical spring c' and a disk c².

A hose is connected by any suitable coupling a⁸ with the section A' of the pipe.

The elbow A³ extends into or through a hole b, made in the floor B, and from it extends down into the cellar the section A² of the pipe. To provide for rotating the section A², it is connected with the elbow by a roller-bearing. As here shown, the section A² of the pipe has screwed into its upper end a ring a⁹, having at its lower end a flange a¹⁰, whose exterior is conical. The upper portion of this ring a⁹ has screwed upon its upper portion a ring a¹¹, whose lower extremity extends almost down to the flange a¹⁰ of the ring a⁹ and, as here shown, is made conical opposite said flange a¹⁰. In the ring a⁹ are a number of holes a¹², arranged in the same horizontal plane, and opposite them in the ring is formed a recess or chamber a¹³. Water flowing through the elbow A³ may to some extent escape and will be deflected outward by the flange a¹⁰ in a film or spray. The ring a¹¹ is provided near its upper end with a flange a¹⁴, which fits in a recess formed in the lower portion of the elbow A³, suitable packing a¹⁵ being employed to make a tight joint. Above this flange the ring a¹¹ may be provided with a rim a¹⁶, and when this construction is adopted a bearing will be provided for it in the elbow A³. The lower end of the elbow A³ has a ring a¹⁷ screwed into it, and between this ring a¹⁷ and the flange a¹⁴ of the ring a¹¹ a number of rollers in the shape of balls are placed. Thus a roller-bearing is provided for facilitating the rotation of the section A² of the pipe independently of the elbow A³.

A rod A⁴ extends through a stuffing-box a¹⁸, formed in the elbow A³. It is capable of rotating and also of moving longitudinally. For the purpose of limiting its upward movement it is provided with a collar a¹⁹, which will coact with a shoulder a²⁰, formed in the neck, which is furnished with the stuffing-box a¹⁸ to limit the upward movement of the rod A⁴. Below the collar a¹⁹ the rod A⁴ is made to interlock with the hub of a spider a²¹, (here shown as formed integral with the ring a¹¹), so that by rotating the rod the ring

a^{11} , and consequently the section A^2 of the pipe, may be rotated. The lower end of the rod A^4 is pivotally connected by a pin a^{22} with a rod A^5 , which extends downwardly 5 through the section A^2 of the pipe. At its lower end the section A^2 of the pipe is provided with a cap A^6 , communicating with a nozzle A^7 . This nozzle is shown as circular in form and is provided with a central longitudinal diaphragm or partition a^{23} . At its inner end it is screwed into a hollow cylindrical piece a^{24} , that fits within a corresponding recess formed in the cap A^6 . Thus provision is afforded for tilting or rocking the 10 nozzle up and down. The cylindrical piece a^{24} is provided with a spider a^{25} , having a rod a^{26} rigidly affixed to it. A pin or screw a^{27} pivotally connects the inner end of this rod a^{26} with the inner end of the rod A^5 . The 15 upper end of the rod A^4 is provided with a handle a^{28} and has also combined with it a swing-arm a^{29} , which is connected to it by a pivot a^{30} , and provided with a clip a^{31} , which will embrace the rod A^4 when the swing-arm 20 is in its uppermost position.

By means of the combination of parts which I have described the section A^2 of the pipe while extended into a cellar may be rotated from the floor above by manipulating the 25 handles a^{28} and the swing-arm a^{29} . Additionally the nozzle A^7 may be tilted or rocked upwardly and downwardly by pulling up or pushing down the rod A^4 . Thus great facility will be afforded for directing a stream of water into any portion of the cellar. The operator of this cellar-pipe will be protected by the film of water escaping over the flange a^{10} at the upper end of the section A^2 of the pipe.

40 What I claim as new, and desire to secure by Letters Patent, is—

1. In a cellar-pipe for extinguishing fires, the combination of two sections connected by means of a hinge and catch so that the two 45 may occupy substantially parallel positions for transportation or positions at an angle for use.

2. In a cellar-pipe for extinguishing fires, the combination of feet or rests provided with 50 sockets or seats for supporting the cellar-pipe, a foot-rod detachably connected to the cellar-

pipe and adapted to fit in said sockets or seats.

3. In a cellar-pipe for extinguishing fires the combination of feet or rests provided with 55 sockets or seats for supporting the cellar-pipe, a foot-rod detachably connected to the cellar-pipe and adapted to fit in said sockets or seats, one of said seats being provided with a spring-actuated disk or bearing. 60

4. In a cellar-pipe for extinguishing fires, the combination with a section adapted to extend into a cellar, of a discharge-nozzle at the end thereof and of means for discharging water close to the top of the said section. 65

5. In a cellar-pipe for extinguishing fires, the combination with a section adapted to extend into a cellar of means comprising a deflecting-flange such as a^{10} for discharging water close to the top of the said section. 70

6. In a cellar-pipe for extinguishing fires, the combination of a rotatable section for extending into the cellar with a rod interlocked therewith and inside of the same, and extending upwardly wholly beyond the cellar-pipe 75 so that it may be manipulated from above.

7. In a cellar-pipe for extinguishing fires, the combination of a section adapted to extend into a cellar, a nozzle fitted thereto so as to be capable of swinging up and down, and a 80 rod passing through the said section of the cellar-pipe and connected with the said nozzle, and passing out of the cellar-pipe where it may be moved longitudinally from above to swing the nozzle. 85

8. In a cellar-pipe for extinguishing fires, the combination of a section adapted to extend into a cellar and capable of being rotated in a complete circle, means for rotating it, a nozzle fitted to said section so as to be capable 90 of swinging up and down, and a rod passing through the said section of the cellar-pipe and connected with said nozzle and passing out of the cellar-pipe where it may be moved longitudinally from above to swing the nozzle. 95

In testimony whereof I have signed my name to this specification in the presence of two subscribing witnesses.

MILTON H. HART.
